United States Patent Office

Des. 197,418
Patented Jan. 28, 1964

197,418

PAIR OF SPECTACLES

Georges Lissac, Paris, France, assignor to La Lunette de Paris, Inc., New York, N.Y., a corporation of New York

Filed Sept. 14, 1962, Ser. No. 71,692

Term of patent 14 years

(Cl. D57—1)

FIG. 1

FIG. 3

FIG. 2

FIG. 4

FIG. 5

FIG. 1 is a perspective view of a pair of spectacles showing my new design;

FIG. 2 is a top plan view thereof;

FIG. 3 is a front elevation view thereof;

FIG. 4 is a right side view thereof; and

FIG. 5 is a view looking in the direction of the arrows 5-5 in FIG. 2.

I claim:

The ornamental design for a pair of spectacles, substantially as shown.
